UNITED STATES PATENT OFFICE.

JOHN WINTER, OF GOSHEN, INDIANA.

SEPARABLE FASTENER.

1,105,738.

Specification of Letters Patent.

Patented Aug. 4, 1914.

Application filed March 26, 1910. Serial No. 551,763.

To all whom it may concern:

Be it known that I, JOHN WINTER, a citizen of the United States, resident of Goshen, in the county of Elkhart and State of Indiana, have made a certain new and useful invention in Separable Fasteners; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a face view of the invention as applied. Fig. 2 is a section on the line 2—2, Fig. 1. Fig. 3 is a detail perspective view of the two fastener plates. Fig. 4 is a detail perspective view of the pin. Fig. 5 is a plan view of one of the fastener plates. Fig. 6 is a detail plan view of a modified form of fastener plate. Fig. 7 is a detail perspective view of a modified form of pin.

The invention has relation to means for detachably fastening carriage curtains to the carriage frame, having for its object to provide an easily operated means of fastening, and one which will obviate to a great extent the rattling and shaking to which such curtains are liable, especially when the wind is at all strong.

Other objects and advantages will hereinafter appear.

The invention consists in the novel construction and combinations of parts, as hereinafter set forth.

In the accompanying drawings, illustrating the invention, the letter *a*, designates a curtain, having an opening therein for use in connection with a fastening stud plate *d*, and with seat plates *b*, *b*, located on opposite sides of the curtain and provided with registering slots *c*, *c*, said stud plate being adapted to be secured to some part of the carriage frame by screws or bolts engaging perforations in the base plate *d'*. The slot *c*, of each plate *b*, is formed with two end portions *e*, and *e'*, of different size, one of said end portions being connected with the other by means of a short neck or passage *e''*, of less size than either of said end portions, and each seat plate having opposite inward extending portions *f*, *f*, located between said end portions. The stud plate *d*, which is designed for use in connection with said seat plates, consists of a base plate *d'*, and a stud

projecting at right angles therefrom and having an outer shouldered head *g²*; a middle shouldered holding portion *g'*, and an inner shank *g*, located between said head and said base plate. The head *g²*, of the stud is adapted in shape and size to pass neatly through the larger end portions of the slots of the seat plates, and terminates in shoulders *h²*. Adjoining this head, immediately next said shoulders, is the holding portion *g'*, which is adapted in shape and size to pass neatly through the smaller end portions of the slots of the seat plates. This holding portion terminates in guard shoulders *h'*, and from it to the base plate extends the inner shank *g*, having a length substantially equal to that of the middle holding portion of the stud, and to the combined thickness of the curtain and its slotted seat plates, said shank being adapted in shape and size to neatly engage the connecting passages of the seat plate slots. The opposing plates *b*, *b*, at each side of the curtain are preferably secured together by means of pointed marginal extensions *b'*, *b'*, of one of said plates, said extensions penetrating the curtain, and being inturned at their free ends at *b²*, *b²*, to engage the edges of the other plate.

In the use of the invention, the head of the stud and the holding portion next the same are passed through the larger ends of the registering seat plate slots, by inward movement of the curtain, until the inner seat plate comes in contact with the base plate *d'*, which forms a stop therefor. The curtain and seat plates are then moved transversely upon the base plate as a guide, when the shank of the stud will pass through the connecting passages of the seat plate slots into alignment with the smaller end portions of said slots, and upon outward movement of the curtain to normal position, the smaller end portions of the seat plate slots are engaged with the holding portion *g'* of the stud, the outer seat plate is brought into engagement with the shoulders *h²* of the stud head, and the curtain is held in a steady and secure manner against lateral shaking. In order to unfasten the curtain, it is necessary because of the small length of the shank of the stud to move the curtain inward until the inner seat plate comes in contact with the stud base, in order that the seat plates may clear the guard shoulders of the holding portion *g'*. This is not liable to happen casually, and the fastening is therefore

designed to be secure. And because in fastening or unfastening, the requisite movements of the curtain are positive and direct, and are guided and limited by the stop surface of the base plate, the invention is regarded as of especial convenience during a wind or in cold or snowy weather.

Having thus described my invention, what I claim as new and desire to secure by Letters Patent is:

A carriage curtain fastening, comprising inner and outer seat plates to be secured to a curtain and provided with registering slots having each end portions of unequal size and a short connecting passage narrower than either end portion, and a stud plate securable in fixed position to the carriage frame and comprising a base plate having a plane stop and guide surface and a stud projecting centrally at right angles to said surface from said base plate and provided with an outer right-angle shouldered head of corresponding size to the larger end

portions of the seat plate slots, a middle right-angle shouldered holding portion adjacent said head of corresponding size to the smaller end portions of said slots, and an inner shank portion of corresponding size to the connecting passages of the slots and extending from said middle portion to said base plate, said inner shank portion being substantially equal in length to said middle holding portion of the stud and to the combined thickness of the curtain and its slotted seat plates, whereby the curtain can only be released from its fastening when its seat plate is in sliding position against and parallel to the stop and guide surface of the base plate of the stud.

In testimony whereof I affix my signature in presence of two witnesses.

JOHN WINTER.
